FILM SPLICER

Donald L. Kristoff, Chicago, Ill., assignor to James Heddon's Sons Corporation, a corporation of Delaware

Application April 17, 1953, Serial No. 24,555

Term of patent 14 years

(Cl. D61—1)

To all whom it may concern:

Be it known that I, Donald L. Kristoff, a citizen of the United States, residing at Chicago, in the county of Cook and State of Illinois, have invented a new, original, and ornamental Design for a Film Splicer, of which the following is a specification, reference being had to the accompanying drawing, forming a part thereof.

Figure 1 is a perspective view of a film splicer showing my new design;

Figure 2 is a top plan view;

Figure 3 is a front elevational view; and

Figure 4 is an end elevational view thereof.

I claim:

The ornamental design for a film splicer, as shown.
